UNITED STATES PATENT OFFICE.

ERNEST JAMES ENTWISLE, OF MORECAMBE, ENGLAND.

MANUFACTURE OF COIR-YARN MATTING AND IN LOOMS THEREFOR.

1,355,320.

Specification of Letters Patent.

Patented Oct. 12, 1920.

Application filed April 12, 1920. Serial No. 373,642.

To all whom it may concern:

Be it known that I, ERNEST JAMES ENTWISLE, a subject of the King of Great Britain, residing at Morecambe, Lancashire, England, have invented certain new and useful Improvements in the Manufacture of Coir-Yarn Matting and in Looms Therefor, of which the following is a specification.

This invention refers to improvements in the manufacture of coir yarn matting and in looms therefor.

In such manufacture as now carried out, the best kinds of coir yarn mattings are woven with a greater number of warp threads per foot in the width of matting, than when weaving the more common qualities.

The warp threads being coarse and uneven, the surface of same being very rough, and the warp threads being also very close together, the crossing of the warp threads at the fell of the fabric is not clean and sharp at the apex of the fell, and consequently the fell of the fabric from one sel-
20 vage to the other, instead of being in a straight line, is irregular, due to unequal degrees of frictional contact between individual warp threads along the width of the fell.

30 In the best quality of weaving, the fell of the fabric should be straight from selvage to selvage, and in order to accomplish this a rod is inserted through the warp shed by manual operation simultaneously with the shuttle passing from shuttle box to shuttle box. The rod is then driven up to the fell of the fabric by the motion of the reed and slay, the said rod being afterward removed from the warp shed by manual operation
35 immediately upon the retreat of the reed. The rod thus forms a straight line of fell from selvage to selvage, along which the weft is laid or pressed by the next forward motion of the reed.

40 Such looms as ordinarily constructed carry a reed and slay operated to and fro in the usual manner by means of a crank and connecting rods, and the reed consequently has a uniform distance of motion in both directions; a shuttle of ordinary construction carries the weft through the warp shed in the usual manner. In operating such a known machine the operator stands near one selvage side of the loom, and as the shuttle
50 is passing through the open warp shed the

operator passes the rod therethrough simultaneously with the passing of the shuttle. The loom being driven by power, the operator releases the driving mechanism, say by shifting the driving belt from the fast to 60 the loose pulley, and the reed by the momentum of the machine, is brought against the rod, presses the latter into the fell of the fabric and the forward motion of the reed and slay are stopped, before the said 65 reed and slay reaches the most forward position, such as when beating up the weft only.

The reed and slay then rebound off the rod and it may be with some assistance from the operator, and upon the rebound of 70 the reed, the operator withdraws the rod from the warp shed, after which the loom is restarted to beat up the weft, the loom continuing in motion until the next crossing 75 of the shuttle takes place when the cycle of manual operations and power motions are repeated. Such operations taking place at every crossing of the shuttle, require considerable skill and attention on the part of the operator and is a laborious process. 80

Now according to the present invention I construct and utilize a rod for the double purpose of inserting the weft through the warp shed of the loom and for the purpose of opening the said warp shed sharply in a 85 straight line and at a wide angle at the fell of the fabric from selvage to selvage.

In carrying out the present invention the weft thread is carried by the forward end of a fell opening rod, so that it can be drawn 90 off a spool located near one end of the loom, and for this purpose the rod may be constructed tubular so that the weft can be threaded through the rod and pass out at the forward end of the said rod, through an 95 eye, to the exterior and so to the fabric.

In order to avoid the necessity, as hitherto, of stopping and causing a reversal of the loom parts, the rod to open the fell sharply and in a straight line (which fell 100 opening rod also carries the weft) is slidably supported in suitable guides, such as by a slotted plate or by parallel rods, the forward end of the fell opening rod passing through a hole in a bearing bracket, and 105 all these supports for the sliding fell opening and weft-carrying rod are suitably secured to the slay of the loom, so that the said rod can be moved along near the face 110 of the reed and through the open warp shed.

The reed is operated in carrying out this invention so that it shall have two distinct front positions, the most forward position being the second operation for beating up the weft only, and the lesser forward position for beating up the fell opening rod of larger sectional dimensions into the fell of the fabric previous to the beating up of the weft itself. Thus when the fell opening rod carrying the weft has passed through the open warp shed, the reed advances, presses the fell opening rod into the fell of the fabric, and opens the warp shed sharply at a wide angle and in a straight line at the fell of the same.

While the reed is in or near this position a swivel shuttle is operated so as to lock the weft from the said fell opening rod to one selvage of the fabric, the reed is then moved by the forward motion of the loom to its rear position, and the fell opening rod is drawn away from the fell of the fabric by the bearing bracket and supporting guides of the said rod on the backward motion of the reed and slay.

The fell opening rod is then mechanically withdrawn from the open warp shed, leaving within the open warp shed a double layer of weft. After such withdrawal of the fell opening rod the reed again comes forward, but on this occasion the reed comes farther forward and beats up the weft threads only into the fell of the fabric. It will be observed that the sectional dimensions of the fell opening rod being much greater than the weft, in order to effect continuous motion of the entire loom the described two distinct front positions of the reed are necessary.

The fell opening rod is made of tubular formation so that the second layer of weft within the tubular fell opening rod shall not become entangled with the warp threads until after the withdrawal of the fell opening rod from the warp shed of the loom.

The invention will now be more particularly described with reference to the accompanying drawing, in which Figure 1 shows diagrammatically the fell opening rod which also carries the weft and means for operating same. Fig. 2 shows a right hand end elevation, the said operating means taken at or about line 2-2 of Fig. 1. Figs 3, 4 and 5 are diagrams illustrating the cycle of operations, and Fig. 6 shows a convenient means for operating a shuttle carrying a selvage thread for the purpose hereafter described. Figs. 3 and 6 are diagrammatic sectional views taken on the lines 3-3 and 6-6 of Fig. 1 respectively. The swivel shuttle is not shown in Fig. 1. Fig. 7 is a transverse sectional view taken adjacent rod 34 of Fig. 6.

A tubular fell opening rod 1 is formed at one end with a nose block 2 having an eye

3 and carries the weft thread 4, the thread passing from the spool 5 through the interior of the said tubular fell opening rod and out at the eye 3.

The fell opening rod 1 is constructed and utilized for the double purpose of opening the said warp shed to a wide angle at the fell of the fabric, and for the purpose of carrying the weft through the open warp shed of a loom.

To effect these objects it is necessary to give a reciprocating movement to the fell opening rod 1 in the direction of its axis into and out of the warp shed and a transverse movement to and away from the fell of the fabric, and accordingly the rod 1 is slidably supported in guides 6 and passes through a bearing bracket 7, both of which are carried on a beam 22 forming part of the slay of the loom. By so mounting the guides 6 and bracket 7 upon the slay, a transverse movement to and away from the fell of the fabric is given to the rod 1 with each movement of the slay.

The means illustrated for traversing the fell opening rod 1 into and out of the warp shed 8 consists of a block 9 fixed to the rod 1 and capable of sliding in the guides 6 carried by the slay of the loom. To this block 9 is attached a rope or belt 10 passing around idle pulleys 11* on the guide 6. The belt 10 passes around and is fixed to a pulley 11 carried in stationary bearings on a bracket 23 attached to one of the main frames 24 of the loom, and the pulley 11 is oscillated by means of a cam 12, lever 13, ruck 14 and pinion 15, as will be well understood upon reference to Figs. 1 and 2. The cam 12 is mounted on a shaft 12* mounted in bearings on the frame 24 of the loom and driven by convenient means.

The reed 16 and slay 22 of the loom is operated so that it shall have two distinct forward positions, thus, when the rod 1 carrying the weft has passed through the open warp shed the reed 16 advances, presses the rod 1 into the fell of the fabric and opens the warp shed sharply to a wide angle (see Fig. 3) and in a straight line from selvage to selvage of the fabric. While the reed 16 is in or near this position a swivel shuttle 17 carrying a selvage thread is operated to lock the weft 4 to the selvage of the fabric. The reed 16 is then moved rearwardly and the rod 1 is simultaneously drawn away from the fell of the fabric by this movement. When the reed 16 is retired by the slay to the position shown in Fig. 4 the rod 1 is withdrawn from the open warp shed, thus leaving two weft threads in the open warp shed. The reed is then advanced to its second and more forward position and beats up the two weft threads in the fell as indicated at Fig. 5.

To effect these two beating up operations

and to obtain the two distinct forward positions of the reed, the slay of the loom is operated by a cam 18 carried on the shaft 12* having a suitable cam race to give the 5 two varying forward positions to the reed 16 for each rotation of the cam. The cam operates upon a lever 19 pivoted at one end, the other end having a connecting rod 20 connecting it to the rocking supports 21 of 10 the slay, so that the necessary two forward positions before described required to be given to the reed shall be carried out in each completee cycle of operations.

At Fig. 6 a suitable means is shown for 15 operating the shuttle 17 which is carried in a circular race 25 fixed on the breast beam of the loom. Reciprocating motion is given to the shuttle by a cam 26 carried on the shaft 12* through the lever 27 fulcrumed at 28, 20 link 29, lever 30, and gears 31, 32, and the shuttle driver 33 which is mounted on a short shaft 34 carrying the gear wheel 32.

When the rod 1 is forced by the slay and reed into the fell of the fabric as in Fig 3, 25 the rotation of the cam 26 rocks the lever 27, and through link 28 the lever 29 rotates gears 31, 32 and the shuttle driver 33 which strikes the heel of the shuttle and moves it in its circular race 25. The shuttle 17 passes 30 over the weft thread carried by the rod 1, and the said rod 1 is then withdrawn from the fell of the fabric by the rearward movement of the slay.

Upon the further rotation of the cam 26 35 the shuttle driver 33 strikes the forward end of the shuttle 17 and brings it back to its first position ready to be passed over the weft thread again at the next stroke of the rod 1.

40 What I claim as my invention and desire to secure by Letters Patent is:—

1. In looms for the manufacture of coir yarn matting; the combination of a rocking slay, means for rocking said slay to first and 45 second forward positions and returning said slay, a combined fell opening and weft carrying rod slidably mounted on the slay, means for reciprocating said rod at proper times in the direction of its axis relatively 50 to said slay to advance said rod through said warp shed and permit said slay to carry said rod in its advanced position bodily into the fell of the fabric to the extent of said first forward position of said slay, 55 means for locking the loop of the weft thread carried by said rod to one selvage of the fabric prior to the withdrawal of said rod from said warp shed, to permit said weft thread left by said rod to be beaten into 60 the fell of the fabric by said second forward motion of said reed and slay.

2. In looms for the manufacture of coir 65 yarn matting; the combination of a rocking slay, means for rocking said slay to first and second forward positions and re-

turning said slay, a tubular rod slidably mounted on the slay and having an eye at its forward end for the exit of the weft thread carried interiorly of said rod, means for reciprocating said rod at proper times 70 in the direction of its axis relatively to said slay to advance said rod through said warp shed to permit said slay to carry said rod bodily into the fell of the fabric to the extent of said first forward position of said slay, means for locking the loop of the weft thread carried by said rod to one selvage 75 of the fabric prior to the withdrawal of said rod from said warp shed, to permit said weft thread left by said rod to be beaten into the fell of the fabric by said second forward motion of said reed and slay.

3. In looms for the manufacture of coir 80 yarn matting; the combination of a rocking slay, means for rocking said slay to first and second forward positions and returning said slay, a fell opening and weft carrying rod carried by the slay, means for reciprocating said rod at proper times in 85 the direction of its axis relatively to said slay to advance said rod through said warp shed to permit said slay to carry said rod bodily into the fell of the fabric to the extent of said first forward position of said slay, a swivel shuttle, means for operating 90 said shuttle to lock the weft carried by said rod to one selvage of the fabric prior to the withdrawal of said rod from said warp shed, to permit said weft thread left by 95 said rod to be beaten into the fell of the fabric by said second forward motion of said reed and slay.

4. In looms for the manufacture of coir 100 yarn matting; the combination of a fell opening and weft carrying rod, a slide block fixed on the rear end of said rod, a rocking slay, a bearing block and guides fixed to said slay to carry said rod and slide block, 105 means for rocking said slay to first and second forward positions and returning said slay, a shaft, bearings on the frame of the machine to carry said shaft, a pulley on said shaft, idle pulleys carried on said slay, 110 an endless cable passing over said pulleys and attached to said slide block fixed on the rear end of said fell opening and weft-carrying rod, a gear wheel on said pulley shaft, a toothed rack engaging said gear wheel, means for reciprocating said toothed 115 rack to give endwise reciprocating motions to said rod at proper times to advance said rod through the warp shed to permit said slay to carry said rod bodily into the fell of the fabric to the extent of said forward 120 position of said slay, means for locking the loop of weft thread carried by said rod to one selvage of the fabric prior to the withdrawal of said rod from said warp shed, 125 to permit said weft thread left by said 130

rod to be beaten into the fell of the fabric by said forward motion of said reed and slay.

5. In looms for the manufacture of coir yarn matting; the combination of a rocking slay, a rotary cam and levers connected to said slay to rock said slay to first and second forward positions and to return said slay, a fell opening and weft-carrying rod 10 mounted on the face of the slay, means for reciprocating said rod at proper times in the direction of its axis relatively to said slay to advance said rod through said warp shed to permit said slay to carry said rod bodily 15 into the fell of the fabric to the extent of

said first forward position of said slay, means for locking the loop of the weft thread carried by said rod to one selvage of the fabric prior to the withdrawal of said rod from said warp shed, to permit said weft 20 thread left by said rod to be beaten into the fell of the fabric by said second forward motion of said reed and slay.

In witness whereof I have hereunto set my hand in the presence of two witnesses.

ERNEST JAMES ENTWISLE.
